[57] CLAIM

The ornamental design for waste separator, as shown and described.

DESCRIPTION

FIG. 1 is a top, left and front perspective view of waste separator, showing my new design;

FIG. 2 is a front elevational view thereof;

FIG. 3 is a rear view thereof;

FIG. 4 is a right side view thereof;

FIG. 5 is a left side view thereof;

FIG. 6 is a top plan view thereof;

FIG. 7 is a bottom view thereof;

FIG. 8 is an exploded view thereof;

FIG. 9 is an enlarged partial cross-sectional view thereof, the spring portion is shown separately for clarity of illustration;

FIG. 10 is a cross-sectional view of a spring portion thereof;

FIG. 11 is a bottom view of the lid;

FIG. 12 is a bottom view of the ring between the lid and top section of the separator;

FIG. 13 is a top plan view of the top section of the separator;

FIG. 14 is a bottom view of the ring clamp of FIG. 8; and,

FIG. 15 is a top plan view of the bottom section of the separator.
